ATTORNEYS.

UNITED STATES PATENT OFFICE.

FRANK H. LA PIERRE, OF EAST ORANGE, NEW JERSEY.

DESIGN FOR A HANDLE FOR NAIL-FILES OR SIMILAR ARTICLES.

SPECIFICATION forming part of Design No. 29,465, dated October 11, 1898.

Application filed June 23, 1898. Serial No. 684,302. Term of patent 7 years.

To all whom it may concern:

Be it known that I, FRANK H. LA PIERRE, a citizen of the United States, residing at East Orange, in the county of Essex and State of New Jersey, have invented and produced a new and original Design for Handles for Nail-Files or Similar Articles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan view of a handle for a nail-file or similar article, the immaterial or non-essential feature of the file being indicated in outline, of my new design; and Fig. 2 is a sectional view taken on line x of Fig. 1.

As shown in the drawings, the leading or material feature of my new design consists in the handle for a nail-file or similar article provided with a line of "polka-dot" ornaments varying in diameter with the variations in the width of the handle.

In said drawings, $a a$ indicate outwardly-convex curves which diverge from the apex b of the handle and then gradually converge

toward the shank, outlining the larger end of the handle. The shank is bounded by long outwardly-concave curves $c c$, which first converge and then diverge, and these are followed by short outwardly-convex curves $d d$ and a bead-shaped ornament e at the end of the handle. 30

The faces of the handle are centrally plain and are convexly rounded, as shown in Fig. 2.

The plain face of the handle is ornamented with a line of polka-dots, one of which, as g , lying at the wide part of the handle, is 40 largest, and the others on either side thereof, as $h h h$, decrease in size as the handle becomes narrower. A polka-dot i of suitable proportions is displayed between the curves $d d$ at the end of the shank of the handle. 45

Having thus described the invention, what I claim as new is—

The design for a handle for a nail-file or similar article, as herein shown and described.

In testimony that I claim the foregoing I have hereunto set my hand this 16th day of June, 1898.

FRANK H. LA PIERRE.
